UNITED STATES PATENT OFFICE.

ROBERT E. CAMPBELL, OF BERKELEY, CALIFORNIA.

WASHING-MACHINE.

1,107,653.

Specification of Letters Patent. Patented Aug. 18, 1914.

Application filed June 11, 1913. Serial No. 773,003.

To all whom it may concern:

Be it known that I, ROBERT E. CAMPBELL, a citizen of the United States, residing at Berkeley, in the county of Alameda and State of California, have invented new and useful Improvements in Washing-Machines, of which the following is a specification.

This invention relates to clothes washing machines, and especially pertains to improvements in the construction of washing tanks of the rockable type and particularly the style or kind on which I obtained Letters Patent of the United States on the 24th day of September, 1907, No. 866,912.

It is the object of this invention to so improve the construction of the washing tank as to increase the efficiency and rapidity of the washing action.

The invention primarily resides in disposing a series of suction cups in the end portions of the tank against which the clothing and liquid in the tank are impelled when the latter is rocked; these cups being provided for the purpose of forcing the liquid through the clothing and for momentarily retaining the clothing against the ends of the tank as the ends move to their uppermost position, and which will act to suddenly release the clothing when one end of the tank reaches its uppermost position and cause them to gravitate rapidly to the lower end of the tank.

The invention further consists of the parts and the construction and combination of parts as hereinafter more fully described and claimed, having reference to the accompanying drawings, in which—

Figure 1 is a side elevation of the invention with parts broken away. Fig. 2 is a detail vertical section on the line X—X of Fig. 1.

In the drawings A represents a rectangular tank formed of any suitable material having a smooth bottom 2 and inwardly inclined ends 3. The top of the tank is enclosed as at 4 and is formed with an opening 5 through which the clothing and liquids are introduced into the tank; a cover 6 being provided for closing the opening 5 during the washing operation. The tank A is pivotally mounted at 7 to a suitable supporting frame 8; the pivotal connection between the frame 8 and the tank A being preferably at a point to one side of the longitudinal center of the tank so that its ends will sweep in arcs of different lengths and

require a short stroke by the operator to tilt the bottom to the angle required to slide the clothes from end to end. A spring 10 having one end attached to the frame 8 and the other connected to a hanger 11 mounted on the underside of the tank A, acts to normally retain the tank A in a horizontal position.

The essence of the present invention resides in disposing a series of suction cups 12 in the ends 3 of the tank A. The cups 12 are preferably arranged in staggered rows across the lower portion of the ends 3 and open to the interior of the tank, as shown in the drawings. The suction cups 12 may be formed of any suitable material and attached to the ends 3 of the tank in any desired manner, but are preferably formed integral with the ends which are usually constructed of sheet metal; the cups 12 being stamped therein. The cups 12 are preferably cylindrical in form with their axes extending perpendicular to the faces of the ends 3 of the tank.

In the operation of the invention the clothing to be washed is placed in the tank together with the necessary liquids and such washing chemicals as may be required. The cover 6 is then secured in place and the tank A is rocked on its pivotal bearing 7 in any suitable manner to cause the clothing and liquid to alternately travel from one end of the tank to the other. As the clothing and liquid is impelled against the open ends of the suction cups at the lower end of the tank 90 the air in the cups will be forced out in such manner that when this end of the tank is elevated, the cups will have a sucking action which tends to hold the clothing against the cups as the end of the tank moves upward. 95 The liquids in the tank will immediately move toward its lower end, and such liquid as may be held in the suction cups, on the upwardly moving end of the tank by the clothing extending over the open ends of the cups, will be gradually replaced by air, which will enter the cups through the clothing and thereby break the vacuum. The moment the sucking action of the cups is overcome by the breaking of the vacuum 100 therein, either from the passage of air through the clothing or by the weight of the clothing, the latter will be suddenly released and caused to travel with considerable rapidity into the body of liquid previously 110 collected at the lower end of the tank and against the open ends of the cups 12. The

clothing in striking the body of liquid in the lower end of the tank causes the liquid to pass through the weaves or mesh of the fabric which have been loosened by the action of the air drawn therethrough by means of the suction cups on the opposite end of the tank. The mass of clothing moving against the open ends of the suction cups at the lower end of the tank with considerable force causes a portion of the clothing being forced a short distance into the open ends of the cups 12, thereby closing the latter, as before described; the clothing on entering the cups displacing a portion of the liquid therein, which displaced portion is forced through the mesh of the clothing extending into the cups. When this lower end is again elevated, the previously described action will take place.

From the foregoing it will be seen that the clothing in the tank A will be subjected alternately to a forced passage of air and liquid through its fabric, thereby insuring a rapid cleansing action. The bottom 2 of the tank A is preferably smooth on its surface so as to offer no hindrance or obstruction to the clothing in passing from one end of the tank to the other; the rapidity with which the clothing falls from one end of the tank to the other having an important bearing in the effectiveness of the machine.

The inclination of the ends of the tank gives it a wedge shaped formation, thereby increasing the tendency of the clothes to ad- here to the end of the tank, and decreasing their tendency to bounce back toward the middle of the tank when impelled against the ends thereof, thus insuring a more concentrated blow being struck the water by the clothes, because of the tendency of the clothes to wedge or jam in the corners.

It will be seen that by momentarily holding the clothing at the ends of the tank as the latter move upward, the liquid therein will move to the opposite end of the tank in advance of the clothing, thus insuring a quantity of liquid being accumulated in the lowermost end of the tank previous to the release of the clothing from the upper end thereof. A draw off cock 13 is mounted in one of the lowermost cups 12 by means of

which the liquids in the tank may be drawn off when desired. It is obvious that the ends of the tank, the cross section of the tank, and the suction cups, may be of any suitable shape other than here shown; the form here illustrated being the preferred form and is subject to many variations.

Having thus described my invention, what I claim and desire to secure by Letters Patent, is:—

1. A clothes washing machine comprising a supporting frame, a washing tank pivoted at one side of its center and adjacent to the bottom to rock longitudinally on said frame, a spring mechanism to maintain the tank in a horizontal position, and a series of cups with their mouths in the planes of the ends of the tank and opening to the interior thereof against which the contents of the tank are impelled on the rocking of the tank.

2. An improved washing machine consisting of a rectangular rockable tank of greater length than breadth having inwardly inclined end portions, a series of suction cups formed in said end portions and opening to the interior of the tank against which the clothing and liquid in the tank are impelled when the tank is rocked for the purpose of forcing the liquid through the clothing and coöperating with the inclined ends for momentarily retaining the clothing against the ends of the tank as they move upward to allow the liquid in the tank to move from end to end thereof in advance of the clothing.

3. In a washing machine, a clothes receiving tank tiltable about a pivot at its lower portion and with end walls and a flat bottom, said walls being provided with a series of inwardly opening, staggered pockets into which clothes will be impinged and held by suction alternately during tilting of the tank.

In testimony whereof I have hereunto set my hand in the presence of two subscribing witnesses.

ROBERT E. CAMPBELL.
